L. E. HARTER

STEAM ACTUATED AIR INJECTOR

Filed July 8, 1926

Inventor:

Lloyd E. Harter;

By Robert W. Sandell,

Attorney.

Patented Apr. 17, 1928.

1,666,136

UNITED STATES PATENT OFFICE.

LLOYD E. HARTER, OF RICHMOND, INDIANA, ASSIGNOR TO CROWN FUEL SAVER COMPANY, OF RICHMOND, INDIANA, A CORPORATION OF INDIANA.

STEAM-ACTUATED AIR INJECTOR.

Application filed July 8, 1926. Serial No. 121,251.

It has been determined, scientifically, that in order to obtain the best results and obtain the maximum amount of heat in the combustion of coal in furnaces that a certain amount 5 of secondary air should be injected over and in contact with the burning coal, thereby supporting the combustion in order to obtain the maximum amount of heat units therefrom and to eliminate soot and smoke, 10 that is to say,—substituting the soot and smoke, which is ordinarily produced, for usable heat. Therefore to overcome said objections, and to obtain the desirable results mentioned, is the paramount object of my 15 present invention.

A further object is to provide means for injecting air, under the desired pressure and with a suitable carrying agent, into the combustion chamber of furnaces or the like in 20 such manner as to obtain the highest degree of efficiency and economy.

And a further object is to provide means for accomplishing said results in an economical manner by means of a construction 25 which is simple in character, strong and durable in its several parts, easily operated and controlled, and which can be manufactured, installed, and sold at a comparatively low price.

One way of carrying out the principles 30 of my invention in a practical and efficient manner is shown in the accompanying drawings, in which—Figure 1 shows my invention in elevation as installed in connection with a furnace which is shown in central 35 vertical section taken through the front and the rear walls thereof.

Figure 2 is a central longitudinal section, 40 taken through the several parts of my invention proper, showing the same in assembled condition. Figure 3 is an end elevation of the concentric rings or cones as assembled alone, with the parts integral therewith. Figure 4 is an exterior view of 45 the assembled parts of my invention. Figure 5 is a horizontal longitudinal section of a portion of the main or distributing nozzle assembly, being a slight modification from the corresponding parts shown in Fig. 4. And Figure 6 is an outside view of the steam-jet nozzle alone.

Similar indices denote like parts throughout the several views.

In order that the construction, the operation, and the several advantages of my in-

vention may be more fully understood and appreciated, I will now take up a detailed description thereof, in which I will set forth the same as comprehensively as I may.

Referring now to the drawings in detail: 60 Letter A indicates the front wall of a furnace, and B denotes the rear wall of the same. Letter C denotes the top, and D denotes the furnace-grate, on which the fuel E is located.

All of said parts are shown merely to make clear the application of my invention in connection therewith.

The invention proper includes a multiple concentric ring or cone assembly, which consists of a plurality of cone-shaped rings 1, 2 and 3, which are of varying dimensions with relation to each other. The smaller end portion of the ring 1 is located in the ring 2, but not in contact therewith. Likewise the smaller end portion of the ring 2 is located in the ring 3, but is not in contact therewith.

The ring 2 is integrally connected with the ring 3 by the two oppositely directed 80 ribs 4. Likewise the ring 2 and the ring 1 are connected by the ribs 5. By the above it will be seen that the rings 1, 2 and 3 are nested together, yet without contact with each other, there being air-intake spaces 85 formed therebetween. Located concentric and flush with the larger end of the ring 1 is the disc 6, shown in Fig. 3, which is integrally connected with the ring 1 by the ribs 7. An aperture 8 is formed through the center of the disc 6, and it is interiorly threaded, for the purpose hereinafter set forth.

The smaller end of the ring 3 terminates in a collar 9, which is offset outward to form a shoulder at the juncture of the ring 3 with said collar 9 for the purpose hereinafter set forth.

The main nozzle assembly comprises a comparatively large and hollow stem 10, one end of which fits snugly in the collar 9 and contacts with said shoulder whereby the inside diameter of the stem 10 is equal with the inside diameter of the smaller end of the ring 3, substantially as shown in Fig. 2.

The stem 10 is detachably secured to the collar 9 by one or more set-screws 15.

Preferably formed integral with and forming a continuation of the stem 10, and formed concentric therewith, is the main air 110

nozzle 11, which is flattened and formed flaring, in order to provide a comparatively long and narrow discharge slot 12.

Connecting the top and bottom portions 5 of the nozzle 11 is a dividing pier 13, which is shown in Figs. 2 and 4 as diamond shape, in cross section. In some instances the pier is formed curved, as the pier 14 shown in Fig. 5, in which latter instance the nozzle is 10 usually longer on one side than on the other, for the purpose hereinafter explained, the same being indicated by the nozzle 16 which is shown in Fig. 5.

The steam-jet nozzle, shown alone in Fig. 15 6, consists of three portions, which are integral with each other: The central disc portion 17, which is adapted to contact flat with the disc 6; the exteriorly threaded nose 18, which is adapted to run into the aperture 8 20 where it is retained by threads; and the larger, exteriorly threaded, stem 19 adapted to have a pipe fitting, as an elbow or a T-fitting, run thereon, as hereinafter explained.

Formed centrally and longitudinally 25 through said steam-jet nozzle is an aperture 20. That portion of the aperture 20 which is near the end of the nose 18 being formed of less diameter than is the remainder thereof, as indicated in Fig. 2.

30 In this instance a T-fitting 21 is threaded onto the stem 19. Threaded onto the second branch of the fitting 21 is an L-fitting 22, which is connected to the steam supply pipe 23, which latter in turn is connected with a 25 suitable steam supply, not shown, and is immaterial to an understanding of this invention.

Where two or more of my devices are employed in one furnace a pipe 24 is extended 40 from the third branch of the fitting 21 to the second, or the third device, so that all may be supplied by the same pipe 23. However where only one of my devices is employed then the pipe 24 may be dispensed with and 45 the third branch of the fitting 21 should be plugged, or the fitting 22 may be connected directly to the stem 19.

Numeral 25 denotes a cut-off valve, whereby the steam may be turned on or off at 50 will. However in practice I usually provide a valve construction which operates automatically with the opening and closing of the furnace door, but this is immaterial to an understanding of my present invention.

55 In practice my device should be disposed at an angle, substantially as shown in Fig. 1, being inserted through, or built into the wall A, and directed downward and inward, whereby the air in issuing from the slot 12 60 will be discharged over the fuel E which is in the process of combustion at that time.

Whenever fresh fuel is placed on the fire carried by the grate D then the valve 25 should be opened, which will permit the 65 steam to be discharged with considerable

force through the steam nozzle or nose 18, with the rings 1, 2 and 3 acting as funnels, carrying the steam into the stem 10.

It will be apparent that the jet of steam issuing from the steam jet nozzle, being 70 under comparatively high pressure, will as it is projected through the rings successively expand and form suctions through the spaces between the rings, whereby a comparatively large volume of air will be taken into the air 75 discharge nozzle, and by reason of the velocity imparted by the steam it will issue from the slot 12 in the form of a heavy air blanket which will cover practically all of the horizontal extent of the interior of the 80 combustion chamber into which it is injected.

For a small size furnace only one of my devices is required, in which case the air delivery nozzle is of the shape shown in Fig. 4. 85 But in large furnaces several of my devices may be employed, as in a series, the same being arranged in a horizontal row and parallel with each other. When a plurality of my injectors are employed in a furnace then 90 the two end air delivery nozzles should be as that shown in Figure 5, whereby a portion of the air from each will be directed more laterally, that is toward the inner corners of the combustion chamber, thereby causing the injected air to be distributed over a greater extent laterally of the interior of the combustion chamber. However the intermediate air delivery nozzles, that is those between the two end air nozzles will be of 95 100 the shape of that shown in Figure 4.

For convenience of description I have employed herein the word "steam," under pressure, as the preferable power for carrying the secondary air into the furnace, however 105 it is to be understood that I am not to be limited thereto, as other carrying elements may be employed such, for instance, as compressed-air.

The force and the suction created by the 110 expanding steam will manifestly cause outside air to be drawn in through the larger open ends of the rings or cones 1, 2 and 3, successively, and carried by the force of the steam into the stem 10, then into the air 115 nozzle, and finally discharged therefrom through the slot 12 in the nature of a heavy blanket of secondary air, with a comparatively small amount of moisture from the steam. While the steam is not a supporter 120 of combustion per se, yet it does add to the effectiveness of the air, with which it is mixed, in retaining the volatile gases where they can be properly impregnated with the injected air besides heating the air to a certain extent before it enters the combustion 125 chamber.

The secondary air injected into and over the fuel under combustion in the furnace causes every part of the fuel, and the gases 130

therefrom, to be consumed and produce usable heat, and entirely dispensing with smoke, thereby greatly increasing the efficiency of the fuel and solving the so called "smoke nuisance".

To summarize: I have found by experience that my invention requires a comparatively small initial expense for installation, and practically no expense for maintenance or repairs; it is as permanent as the boiler or the furnace with which it is used; it meets all fire preventive ordinance and requirements; it dispenses with smoke and soot, and the consequent cleaning of flues; it makes possible the use of a cheaper grade of fuel, and requires a less amount of fuel to be used; it increases the draft and causes steam to be raised more quickly; and it is adapted to be used in various types of furnaces or combustion chambers and can be installed either singly or in multiple.

I desire that it be understood that various changes may be made in the several details herein set forth without departing from the spirit of the invention or sacrificing any of the advantages thereof which are new and useful and which involve invention.

Having now fully shown and described my invention, what I claim and desire to secure by Letters Patent of the United States, 30 is—

A secondary air injector, to be employed in connection with a furnace or the like, and comprising a plurality of cone-shaped rings spaced apart and integrally connected to 35 form air inlets between each two and leading from the outside to the interiors thereof, a steam jet nozzle concentric with said rings and adapted to direct a jet of steam through the centers of all of said rings, means for detachably connecting said nozzle with one of said rings, a hollow stem connected to another one of said rings which is most remote to the ring to which said nozzle is connected, an air discharge nozzle extending 40 from the outer end of said stem and formed flattened and fan-shaped horizontally with a slot formed through the end thereof for the discharge therethrough of air, and a dividing pier connecting the upper and the lower 45 portions of said air discharge nozzle.

In testimony whereof I have hereunto subscribed my name.

LLOYD E. HARTER.
